UNITED STATES PATENT OFFICE.

FRANCIS I. DU PONT, OF WILMINGTON, DELAWARE.

EXPLOSIVE PROJECTILE.

1,015,945.

Specification of Letters Patent. Patented Jan. 30, 1912.

Application filed July 12, 1911. Serial No. 638,058.

To all whom it may concern:

Be it known that I, FRANCIS I. DU PONT, a citizen of the United States, residing at Wilmington, county of Newcastle, and State 5 of Delaware, have invented a new and useful Improvement in Explosive Projectiles, of which the following is a full, clear, and exact description, reference being had to the accompanying drawings, which form a part 10 of this specification.

The object of my invention is to provide means for exploding a projectile, for instance a shrapnel shell, as soon as it has traveled a given distance from the gun.

15 In a patent issued to me June 20, 1911, No. 995,635, I have set forth and claimed a projectile embodying a fly-wheel within the shell and rotatable relatively thereto on its longitudinal axis, and means geared to and 20 operable by the fly-wheel adapted to effect the operation of firing mechanism after a predetermined number of revolutions of the shell around the fly-wheel. As the projectile, in traveling a given distance, will rotate a given number of times, the gearing may be adjusted so that the parts will 25 function after such number of revolutions, and therefore the firing mechanism will operate after the projectile has traveled such 30 given distance. In said Patent No. 995,635, and also in two later applications, one filed by me May 29, 1911, Serial No. 630,009, and another filed by me July 7, 1911, Serial No. 637,308, I have illustrated and described 35 different embodiments of my broad invention, all, however, having in common the principle of a fly-wheel which, by virtue of its own inertia, does not partake of the rotary movement imparted to the shell as it 40 leaves the muzzle of the gun.

The object of the present invention is identical, in a broad sense, with that of my inventions referred to, and embodies the underlying mode of operation specified; but it 45 has for its more specific object the provision of means adapted to coöperate with the force of inertia to overcome with more absolute certainty any tendency that may exist for the fly-wheel to partake even in slight de- 50 gree of the rotary motion of the outer shell. To this end, I have devised a construction whereby the force of inertia is supplemented by means, operating on the princi-

ple of a gyroscope, adapted to prevent rotation of the fly-wheel.

55

A preferred embodiment of my invention is shown in the accompanying drawings, in which—

Figure 1 is a longitudinal section through the projectile; and Figs. 2 and 3 cross-sections on the lines 2—2 and 3—3 respectively of Fig. 1.

a is the body of the shell.

b is the base, which is threaded into the body. Arranged concentric with the longitudinal center or axis of the shell is a tube *c* having secured to its lower end a fly-wheel *d*. At the rear of the fly-wheel is a ball bearing *e* between it and the base of the shell. At the front of the tube is a ball bearing *f* between it and the point of the shell. Thus the tube *c* and fly-wheel *d* are freely rotatable relatively to the shell on an axis coincident with the longitudinal center line of the shell. Threaded in the point of the shell is a plug *g* having secured thereto a screw *h* extending within the tube along the axis of the shell. On the screw *h* is a nut *i* having projections *j* engaging longitudinally extending grooves or recesses *k* formed in the internal wall of the tube *c*.

The plug *g* is provided with a primed rear face, and the nut *i* with a primed front face. For example, these opposing surfaces may carry friction materials, *m* and *n*, respectively, such as red phosphorus and a chlorate mixture, which upon sliding contact with each other fire, as described in my prior application No. 630,009, or one member may carry a match head composition while the other contacting member may be roughened by grooving, as also described in the same application. The rear end of the screw extends into a central hole in the fly-wheel *d*. The plug *g* may be unscrewed and the screw *h* and nut *i* withdrawn and the nut adjusted on the screw at any desired distance from the primed face of the plug.

o is an annular internal casing that is intended to contain explosive material *p*, and a number of balls *r* may be confined therein, preferably along the inner wall of the shell, which balls will be scattered when the explosive within the casing explodes.

Threaded into the fly-wheel *d* are studs *s*. 105 These studs extend radially to the axis of

the shell. Freely rotatable on the shafts are friction wheels *t* having conical peripheries engaging an annular conical friction driving surface *v* on the front wall of the base of the shell.

5 Previous to firing the projectile, the plug *g* is unscrewed and the screw *h* and nut *i* withdrawn and the nut positioned on the screw at a point determined by the desired 10 distance from the muzzle of the gun at which the bursting is to take place. When the projectile starts its forward movement, two distinct movements of the shell relatively to the fly-wheel and tube occur. In 15 the first place, while the plug *g* and screw *h* rotate with the shell, the fly-wheel *d* (as well as the tube *c* and wheels *t* which in effect virtually form part of the fly-wheel) does not get started by the force that 20 determines the rotation of the shell and by reason of their inertia remain stationary. In the second place, the ball bearings, particularly the rear bearing *d*, are so arranged as to permit a slight longitudinal movement 25 of the fly-wheel and tube relatively to the shell; by reason of which these parts do not immediately partake of the forward movement of the shell, causing them to move back and press the wheels *t* into contact 30 with the friction cone *v*. The result is that, the instant after the shell starts its forward movement, a rapid movement of rotation on their own axes is imparted to these wheels. As the shell leaves the gun and begins its 35 flight, air resistance tends to retard the movement of the shell, but no such force being operative against the forward movement of the fly-wheel *d* and tube *c*, these parts move forward and free the wheels *t* 40 from contact with their driving cone *v*. At this time these wheels are rotating at a high rate of speed, by virtue of which they strongly resist any change of direction of their axes. Consequently they strongly 45 resist any bodily rotation around the axis of the shell, and consequently the fly-wheel *d*, tube *c* and nut *i* are held from rotation even if otherwise the rotation of the shell would tend to overcome to any extent their own 50 inertia. It will therefore be understood that from the time the shell starts its forward movement, the nut *i*, which is held from rotation by the tube *c*, is fed forward by the rotation of the screw *h*. After a 55 certain number of revolutions, corresponding to the number of turns in the screw thread between the opposing surfaces of the nut *i* and plug *g*, the primed face of the nut contacts with the primed face of the plug. 60 This occurs at a time when the shell *a* with the plug *g* is rotating at a high velocity while the nut *i* is not rotating. The result is that the opposing faces of the nut and plug 65 slide one upon the other and ignite the priming material. The fire flashes through the

holes *x* in the tube *c* and the holes *y* in the casing *o* and ignites the explosive material *p*.

It will be understood that while the principle of inertia of means within the shell rotatable relatively to the shell's axis and geared to the shell so as to control the operation of firing mechanism, is retained in the present invention, it is supplemented by, and to a greater or less extent subordinated to, the gyroscopic action tending to hold such means from bodily rotation. Among the advantages resulting from reliance upon gyroscopic force are: First, rotation of the fly-wheel is prevented with more certainty 70 and completeness; second, the weight of the fly-wheel may be reduced to a minimum, that is, to an extent that would not be desirable if its own inertia were to be exclusively depended upon to hold it from rotation. Indeed the invention does not necessitate the employment of the fly-wheel as such, and the wheels themselves and the parts carrying the same and gearing with the shell may be so light in weight that 75 their function as a fly-wheel becomes of minor or no importance except, perhaps, in the initial operation of the mechanism.

Having now fully described my invention, what I claim and desire to protect by Letters Patent is:

1. In a projectile, the combination with the shell, of a member within the shell rotatable on an axis at an angle to the longitudinal axis of the shell and also rotatable bodily relatively to the shell on the latter's longitudinal axis, normally inoperative firing means and intermediate mechanism between said firing means and said member operable in the latter's relative bodily movement of rotation to render said firing means operative.

2. In a projectile, the combination with the shell, of mechanism freely rotatable relatively to the longitudinal axis of the shell, mechanism gearing therewith rotatable with the shell, and firing means carried by both said mechanisms arranged to function with each other after a predetermined number of revolutions of the shell 100 around its axis, the first named mechanism including a member rotatable upon an axis at an angle to the shell's axis.

3. In a projectile, the combination with the shell, of mechanism mounted in the shell so as not to partake of its movement of rotations, said mechanism including a member mounted to turn on an axis at an angle to the shell's axis and adapted in the rotation of the shell to be rotated thereby 110 on its own axis, and primer-exploding means controlled in its operation by said mechanism.

4. In a projectile, the combination with the shell, of mechanism rotatable with the 120

shell, mechanism geared therewith and mounted in bearings in the shell so as not to partake of its movement of rotation and including a member rotatable on an axis at an angle to the shell's axis and adapted in the rotation of the shell to be rotated thereby on its own axis, and firing means controlled in its operation by said mechanisms.

5. In a projectile, the combination with the shell, of a member rotatable on an axis at an angle to the longitudinal axis of the shell and also rotatable bodily relatively to the shell on the latter's longitudinal axis and adapted in the rotation of the shell to be rotated thereby on its own axis, normally inoperative firing means, and intermediate mechanism between said member and said firing means, operable in the relative bodily rotation of said member to render said firing means operative.

6. In a projectile, the combination with the shell, of mechanism mounted in the shell so as not to partake of its movement of rotation, mechanism gearing therewith rotatable with the shell, the first named mechanism including a member adapted in the rotation of the shell to be rotated thereby on an axis at an angle to the shell's axis, and firing means carried by both of said mechanisms and arranged to function with each other after a predetermined number of revolutions of the shell around its axis.

7. In a projectile, the combination with the shell and a part rotating therewith, of mechanism mounted in the shell so as not to partake of its movement of rotation and movable longitudinally of the shell, said mechanism including a member mounted to turn on an axis at an angle to the shell's axis and adapted in the rearward movement of said mechanism upon firing, to engage, and be rotated on its own axis by, said rotatable part, and primer-exploding means controlled in its operation by said mechanism.

8. In a projectile, the combination with the shell, of mechanism rotatable with the shell, mechanism gearing therewith longitudinally movable in the shell and mounted therein so as not to partake of its rotary movement and including a member adapted, in the rearward movement of the last named mechanism upon firing, to engage a part of the first-named mechanism and be rotated thereby on an axis at an angle to the shell's axis, and firing means controlled in its operation by said mechanisms.

9. In a projectile, the combination with the shell, of a member mounted in the shell so as to have three movements relatively thereto, namely, a relative bodily movement around the longitudinal axis of the shell, a positive rotary movement about an axis at an angle to the shell's axis, and a longitudinal movement; a part rotatable with the

shell and adapted to engage and rotate said member in the backward movement thereof resultant upon firing the shell, and means connected with said member including gearing and a primer-exploding device.

10. In a projectile, the combination with the shell, of a member mounted in the shell so as to have three movements relatively thereto, namely, a relative bodily movement around the longitudinal axis of the shell, a positive rotary movement about an axis at an angle to the shell's axis, and a longitudinal movement; a part rotatable with the shell and adapted to engage and rotate said member in the backward movement thereof resultant upon firing the shell, normally inoperative firing means, and intermediate mechanism between said firing means and said member, operable by the latter in its relative bodily movement of rotation to render the firing means operative.

11. In a projectile, the combination with the shell, and a part rotatable therewith, of mechanism mounted in the shell so as not to partake of its movement of rotation and be capable of a limited longitudinal movement relatively to the shell, mechanism gearing therewith rotatable with the shell, the first named mechanism including a member adapted upon firing the shell to move backward and engage, and be rotated by, said part rotatable with the shell, on an axis at an angle to the shell's axis, and firing means carried by both of said mechanisms and arranged to function with each other after a predetermined number of revolutions of the shell around its axis.

12. In a projectile, the combination with the shell, of a gyroscope mounted in bearings therein so as not to partake of the rotary movement of the shell and having a rotatable part at an angle to the shell's axis, means operable in the rotation of the shell to rotate said part whereby the body of the gyroscope is held from rotation with the shell, and firing means connected with, and controlled in its operation by, said gyroscope.

13. In a projectile, the combination with the shell, of a gyroscope mounted in bearings therein so as not to partake of the shell's rotary movement and having a rotatable part at an angle to the shell's axis, means operable in the rotation of the shell to rotate said part, and primer exploding means controlled in its operation by said gyroscope and arranged to function after a predetermined number of revolutions of the shell around the gyroscope.

14. In a projectile, the combination with the shell, of a gyroscope mounted in bearings therein so as not to partake of the shell's rotary movement and having a rotatable part at an angle to the shell's axis, means operable in the rotation of the shell

to rotate said part, mechanism connected with the non-rotatable part of the gyroscope and with the shell and geared together, and firing means operable by said mechanism and adapted to function after a predetermined number of revolutions of the shell around the gyroscope.

15. In a projectile, the combination with the shell, of a gyroscope rotatably mounted on the shell's longitudinal axis and movable longitudinally of said axis, whereby in firing the gyroscope moves rearward in the shell, a part rotating with the shell and adapted to engage said gyroscope in its rearward movement and start its operation, and firing means connected with and controlled in its operation by said gyroscope.

16. In a projectile, the combination with the shell, of a gyroscope mounted in bearings therein so as not to partake of the shell's rotary movement and having a rotatable part at an angle to the shell's axis, said gyroscope being also movable longitudinally of the shell, means operable in the rotation of the shell to engage said part in the rearward movement of the gyroscope consequent upon the firing of the shell and rotate said part on its axis, and primer-exploding means controlled in its operation by said gyroscope and arranged to function after a predetermined number of revolutions of the shell around the gyroscope.

17. In a projectile, the combination with the shell, of a gyroscope mounted in bearings therein so as not to partake of the shell's rotary movement and having a rotatable part at an angle to the shell's axis, said gyroscope being also movable longitudinally of the shell, means operable in the rotation of the shell to engage said part in the rearward movement of the gyroscope consequent upon the firing of the shell and rotate said part on its axis, mechanism connected with the non-rotatable part of the gyroscope and with the shell and geared together, and firing means operable by said mechanism and adapted to function after a predetermined number of revolutions of the shell around the gyroscope.

18. In a projectile, the combination with the shell, of a fly-wheel rotatably mounted therein on an axis coincident with the longitudinal axis of the shell, and movable longitudinally of the shell, wheels carried by said fly-wheel and rotatable on axes extending radially to the shell's axis, said shell having a driving face adapted in the rearward longitudinal movement of the fly-wheel to contact with the driving faces of said wheels and rotate them on their axes,

mechanism connected with the fly-wheel and with the shell and geared together, and firing means operable by said mechanism and adapted to function after a predetermined number of revolutions of the shell around the fly-wheel.

19. In a projectile, the combination with the shell, of a fly-wheel rotatably mounted therein on an axis coincident with the longitudinal axis of the shell and movable longitudinally of the shell, friction wheels, having a conical periphery, carried by the fly-wheel and rotatable on axes extending radially to the shell's axis, the base of the shell having an annular conical friction driving surface adapted in the rearward movement of the fly-wheel to contact with the peripheries of said wheels and rotate them on their axes, mechanism connected with the fly-wheel and the shell and geared together, and firing means operable by said mechanism and adapted to friction after a predetermined number of revolutions of the shell around the fly-wheel.

20. In a projectile, the combination with the shell, of a gyroscope mounted in bearings therein so as not to partake of the shell's rotary movement and having a rotatable part at an angle to the shell's axis, means operable in the rotation of the shell to rotate said part, a screw rotatable on its own axis with the shell, a nut on the screw connected with, and held from rotation by, the gyroscope, and priming means operable by the nut after the screw has made a predetermined number of revolutions.

21. In a projectile, the combination with the shell, of a fly-wheel rotatably mounted therein on an axis coincident with the longitudinal axis of the shell and movable longitudinally of the shell, wheels carried by the fly-wheel and rotatable on axes extending radially to the shell's axis, said shell having a driving face adapted in the rearward longitudinal movement of the fly-wheel to contact with the driving faces of said wheel and rotate them on their axes, a tube secured to the fly-wheel, a screw extending through said tube, a nut on the screw slideable in longitudinal guides on the tube, and priming means operable by the nut in its travel along said screw.

In testimony of which invention, I have hereunto set my hand, at Philadelphia, on this 10th day of July, 1911.

FRANCIS I. DU PONT.
